COMBINED HEADPHONE AND RADIO RECEIVER

Gilbert King-Hung Lung, Kowloon, Hong Kong, assignor
to Sonway Manufacturers Limited, Kowloon, Hong
Kong

Filed Aug. 3, 1973, Ser. No. 385,575

Claims priority, application Great Britain Feb. 5, 1973

Term of patent 14 years

Int. Cl. D14—01, 03

U.S. Cl. D26—14 H

FIG. 1 is a side elevation of a combined headphone and radio receiver showing my new design;

FIG. 2 is a top perspective view thereof; and

FIG. 3 is a bottom perspective view thereof.

I claim:

The ornamental design for a combined headphone and radio receiver, as shown.
